UNITED STATES PATENT OFFICE

110,157

DESIGN FOR A COMBINED STEERING WHEEL KNOB AND BRACKET

John Sinko, Oak Park, Ill.

Application March 21, 1938, Serial No. 75,998

Term of patent 14 years

To all whom it may concern:

Be it known that I, John Sinko, a citizen of the United States, residing at Oak Park, county of Cook, and State of Illinois, have invented a new, original, and ornamental Design for a Combined Steering Wheel Knob and Bracket, of which the following is a specification, reference being had to the accompanying drawing, forming a part thereof, in which:

Figure 1 is a side elevational view of a combined steering wheel knob and bracket embody-

ing the invention, the dotted lines indicating a knob; Fig. 2, a front elevational view of the same; and Fig. 3, a plan view.

The characteristic features of my design reside in the portions illustrated in solid black lines in the drawing.

I claim:

The ornamental design for a combined steering wheel knob and bracket, as shown and described.

JOHN SINKO.
